Patented Feb. 28, 1922

FIG. 1.

FIG. 2.

Director:
Thomas Albert Mills
By C. L. M. Bryant, Jr.
Attico

UNITED STATES PATENT OFFICE.

THOMAS ALBERT MILLS, OF CLAPHAM, LONDON, ENGLAND, ASSIGNOR TO ZOECROME LIMITED, OF LONDON, ENGLAND, A BRITISH COMPANY.

COLOR CINEMATOGRAPHY.

1,407,875.

Specification of Letters Patent. Patented Feb. 28, 1922.

Application filed November 13, 1920. Serial No. 423,961.

To all whom it may concern:

Be it known that I, THOMAS ALBERT MILLS, a subject of the King of Great Britain, residing at 72 Manor Street, Clapham, in the county of London, England, have invented certain new and useful Improvements in or Relating to Color Cinematography, of which the following is a specification.

This invention relates to an improved method of producing cinematograph films of the type in which each individual picture or element of the film is a complete color rendering of the subject.

According to this invention there are produced upon the negative film (by the aid of suitable color screens) a set of images of full or normal size which will be referred to hereinafter as key images and interposed sets of small sized color giving images, each preferably of half the linear dimensions of a key image. The small color giving images may be three in number, corresponding to the usual triple division of colors, and the key image taken without a color screen so as to give the black and white effect only. Or the key image may also be a color image, giving say the blue in the resulting positive film, either alone or, by a double printing, the blue and a similar black and white or true key image, and only two small images may be produced. Each key image and its associated small images are taken simultaneously through separate lenses and, as the lens for the large image has to have a correspondingly greater focal length and if employed to give a direct image would form an obstruction for the small images, the increased focal length is preferably provided for by a prism or other reflector, allowing all the lenses to lie in the same plane. This displaces the key image from its corresponding color images and therefore between the key and color images of one exposure are interposed the key and color images of other exposures.

In producing the positive film from the original negative the latter is moved at each operation through a distance equal to a key image and the following small color images, closing up the key images on the positive film so that they are reproduced in succession without the interposition of the color images, these being afterwards enlarged and superposed. The reproduction, if the key image is to be in one of the colors employed,

say blue, is suitably colored or dyed, but if the key image is black and white the usual process only is employed. Or the same large image may be reproduced twice, once as a black and white image and once in color. The reproduced key film is then coated with a sensitive emulsion and one of the color sets of images is then enlarged to the key size and superposed upon the key images, the new positive images being colored to the required color, complementary to that of the color screen employed for the negative. The next set of color giving pictures is similarly superposed and, in the case of the process employing black and white key images and three colors, the third set of color images is then superposed, with the result that the finished film is a complete color rendering of the subject and can be projected by the usual apparatus upon the screen. The apparatus employed for producing the positive may be of the type described in the specification of British Patent No. 16353 of 1913 (Middleton). It is to be understood that the term "key image" is used in a wide sense as the image which is originally taken of full size and thus serves as the most important image in giving definition to the picture, but it is not necessarily an opaque or black and white image in the positive picture.

In order that the said invention may be clearly understood and readily carried into effect, the same will be more fully described with reference to the accompanying drawings, in which:—

Figure 1 is a diagram illustrating the production of a negative having a set of key images and three sets of color giving images;

Figure 2 is a similar diagram illustrating the case in which the key image is also one of the color giving images.

Referring first to Figure 1, A is the negative film. B, B are the key images of full size. C, C, C, are three sets of half size color giving images arranged with one central image and two images side by side. D, D' are the camera lenses, of which the larger lens D is of twice the focal length of the smaller lenses D'. E is a prism reflector. The lenses are arranged as shown at the right of the figure, the small lenses forming an inverted triangle below the large lens. The reflecting prism E is arranged so that

the pencil of light from the large lens D, indicated by dotted lines, is reflected from the lower and upper surfaces e , e' and on to the film A, the distance of two full images 5 above the images due to the lenses D' . The length of the path from the large lens to the film is twice that of the direct path from one of the small lenses to the film so that the increased focal length of the large lens is 10 provided for while allowing the lenses to be placed in the same plane. The shutter mechanism and the color screens are not shown as they may be of ordinary type.

In Figure 2 the key pictures B' are produced by the aid of a color screen, say red, 15 and instead of separating the images by a full picture width as in Figure 1 the separation is of half a picture width only, to accommodate a pair of small color images C' 20 taken through the two other color screens of the set of three. The small lenses D^2 are placed symmetrically below the large lens D. Otherwise the arrangement is as in Figure 1, and the prism reflector E doubles the 25 distance of the path from the lens D to the film.

In producing a positive from the negative film as shown in either Figure 1 or Figure 2 the key image is thrown upon the positive 30 film and the negative film is moved for each exposure in the apparatus through the space of two pictures or a picture and a half according to whether the arrangement of Figure 1 or Figure 2 is employed, the positive 35 film being moved one picture space at a time. The positive film with the key images on it is then developed and fixed and may be varnished before sensitizing again. If the key image is also a color one the positive 40 film is colored to, say, blue. Or a black and white key image may be used and a second printing from the large images taken and colored.

The resensitized positive film is again exposed and the enlarged images of one of 45 the sets of small color images superposed upon the key images. The lens system employed for copying is arranged to give the required enlargement, while for the key pictures, the original and reproduced images 50 are of substantially equal size. The images B and C having been relatively displaced by the action of the reflector, the color images superposed must be those separated by the 55 intermediate images, as indicated by the dotted lines in the drawings, so that the color images shall be those taken by the same exposures as the key images on which they are superposed. The positive film is 60 colored and resensitized again for the second color set, the operations being repeated where a key picture and three small pictures are employed as in Figure 1. The final result is a positive film fully colored and 65 adapted to be projected by the usual pro-

jecting apparatus. The three color system has been taken as the basis of the method described and illustrated, but it is obvious that other color systems may be used.

Owing to the fact that the key images and 70 the color images are taken simultaneously the original film should be moved more rapidly than is the case with an ordinary film, since the space of two or of one and a half ordinary pictures has to be covered between 75 each exposure, while the colored positive is moved at the normal speed for projection. Since the key image is of full size the projection on the screen gives a clearness of 80 impression substantially as good as that of the ordinary uncolored picture. To obtain this clearness it is not essential that the color producing images should be so sharp, so that the smaller scale on which they are taken does not materially affect the sharpness of the result and the great advantage 85 is obtained that the color effect is given by an addition to the length of the negative film of only 50 or 100 per cent according to the color system employed. The disturbing 90 rainbow effect produced when color images are taken successively is also entirely eliminated by the simultaneous exposure of a complete set of images.

What I claim and desire to secure by Let- 95 ters Patent of the United States is:—

1. A method of making cinematograph films which consists in producing upon the negative film a set of full sized images with small sized interposed images by simultaneous exposure of a full sized image and associated small sized images and producing from the said negative film a positive film by superposing in succession upon the said positive film the negative images, all brought to the said dimensions, and suitably coloring the different superposed positive images, for the purpose specified.

2. A method of making a negative film for the production of a colored cinematograph positive film, which consists in producing a succession of alternating key images of full size and color giving images of small size, by a system of lenses and color screens, and providing for the greater focal length required for the full sized images by reflecting the beam between the corresponding lens and the film.

3. A method of making colored cinematograph films which consists in producing upon a negative film a succession of full sized key images and interposed small sized color giving images whereby a plurality of color giving images occupy the length of film not greater than that of a single key image, reproducing from the negative film a positive film by moving the negative film in the positive producing apparatus in steps equal to a complete group of images and correspondingly moving the positive film in steps of

one image at a time, repeating the succession of reproducing operations for each color employed and enlarging the small sized color giving images of the negative film to the same size as the key images on the positive film, and, after a complete exposure of the positive film, coloring the positive images re-sensitizing the said film and producing a fresh set of images which are also colored repeating the operations until the complete colored picture is obtained.

4. A negative cinematograph film for the production of a colored positive film, which negative film comprises a succession of key images of full size along with a simultaneously taken succession of color giving images of small size, whereby a plurality of color giving images occupies a length of film not greater than that of a single key image, for the purpose specified.

5. A negative cinematograph film for the production of a colored positive film, which negative film comprises a succession of key images of full size along with a simultaneously taken succession of color giving images of half size, whereby a plurality of color giving images occupies a length of film not greater than that of a single key image, for the purpose specified.

6. A negative cinematograph film for the production of a positive colored film which negative film comprises a succession of full sized key images having interposed between each pair of full sized images a plurality of half sized color giving images obtained by simultaneous exposure with corresponding key images, whereby a plurality of color

giving images occupies a length of film not greater than that of a single key image, for the purpose specified.

7. A negative cinematograph film for the production of a positive colored film, which negative film comprises a succession of full sized key images having interposed between each pair of full sized images a group of three half size color giving images obtained by simultaneous exposure with corresponding key images, said group taking up the same length of film as the key images, for the purpose specified.

8. A negative cinematograph film for the production of a colored positive film, which negative film comprises a set of full sized images and interposed small sized images each of which small sized images is taken by simultaneous exposure with a full sized image separator from the said small sized image by interposed images taken at different exposures, the small size images between two large images occupying a length of film not greater than that of a single key image, for the purpose specified.

9. Apparatus for the production of a negative film for use in obtaining a colored positive film, which apparatus comprises a lens of focal length adapted to give cinematographic images of full size, a plurality of lenses of shorter focal length coplanar with the first lens and adapted to give images of smaller size, and a reflector interposed between the film and the said first lens so as to provide for the increased focal length, for the purpose specified.

THOMAS ALBERT MILLS.
